UNITED STATES PATENT OFFICE.

RAFAEL DIAZ BUITRAGO, OF NEW YORK, N. Y.

BUBBLE-BLOWER.

1,215,617.

Specification of Letters Patent. Patented Feb. 13, 1917.

Application filed May 8, 1916. Serial No. 96,054.

To all whom it may concern:

Be it known that I, RAFAEL DIAZ BUITRAGO, a citizen of the United States of America, and a resident of the borough of Manhattan, city, county, and State of New York, have invented certain new and useful Improvements in Bubble-Blowers, of which the following is a specification.

My invention relates to improvements in bubble blowers and comprises a device of that nature having a reservoir for the bubble-forming solution which is an integral part of the complete structure and is arranged in a novel and improved manner with respect to the blowing tube. My invention further comprises an improved form of cup or seat for the bubble; improved means for establishing or cutting off, at will, communication between the blowing pipe and the said reservoir; and other features, all as hereinafter described and more particularly pointed out in the appended claims.

The objects of my invention are to improve the construction of bubble blowers; to produce a device which is neat and compact, and which may be used without dripping of the solution and without detriment to the clothing of the user or to surrounding objects; to so construct the device that the blowing of very large bubbles may be possible; and generally to produce a device which, while compact and neat in appearance is simple in construction, may be produced at small expense, and is not readily broken or otherwise injured.

I will now proceed to describe my invention with reference to the accompanying drawings, and will then point out the novel features in claims. In the drawings:

Figure 1 shows a front elevation of the device and Fig. 2 shows a central longitudinal section thereof on a plane at right angles to that of Fig. 1.

In the drawings 1 designates a tube, usually formed of metal, and having a readily detachable mouth piece 2. 3 designates a bent tube, also usually formed of metal, secured to the lower end of the tube 1 and terminating in an enlargement 4 pro-

vided with a flaring cup 5, forming the 50 bubble seat. 6 designates a solution reservoir provided with a central tube 7 through which the tube 1 (which tube is the blowing tube) passes. The reservoir 6 has at one side a filling aperture normally closed 55 by a cap 8 having within it a pressure-balancing orifice 9.

The tube 7 has near its lower end, an orifice 10, and the pipe 1 has a corresponding orifice 11. When these two orifices 10 60 and 11 are in registry the blowing pipe 1 is in communication with the reservoir 6, and solution within that reservoir may flow down through tube 3 into the enlargement 4 at the base of the cup 5; flow being facilitated by the inductive action of air blown through tube 1; for the holes 10 and 11 are preferably so small as to be capillary in character so that little or no flow will occur through them except as a result of 70 such inductive action. The tube 1 is adapted to be rotated through a small angle within the tube 7, and is provided with a pin 12 working in a slot 13 of a portion of the tube 7 projecting out beyond the reservoir 75 6. When the tube 1 has been turned with respect to the tube 7, so that the pin 12 is at one side of the slot 13, orifices 10 and 11 are in registry. When the tube 1 is turned with respect to the tube 7 so that the pin 80 12 is at the opposite end of the slot 13, the orifices 10 and 11 are out of registry and communication between reservoir 6 and tube 1 is shut off.

The pin 12 and slot 13 not only serve to 85 control position of the reservoir with respect to the tube 1, and therefore to control flow from the reservoir, but also serve to hold the reservoir in position, longitudinally, with respect to the tube 1. As clearly shown in 90 Fig. 1, there is, at the center of the slot 13, a gap permitting the reservoir to be moved longitudinally of the tube 1, out of engagement with the pin 12, and therefore permitting the reservoir to be removed from 95 the tube 1 after the bent tube 3 has been unscrewed from tube 1.

As will be obvious from the drawings,

when the reservoir 6 has been filled, placing of the orifices 10 and 11 in registry for a moment (the hole 9 being open) permits a portion of the solution within the reservoir 5 to flow into the pocket 4. The amount so flowing may be regulated by closing the hole 9 after it is thought that a sufficient amount of the fluid has passed out. This hole 9 may be closed readily by the finger of the 10 user, thus stopping the flow from the reservoir more conveniently than could be done by turning the tube 1 so as to move orifices 10 and 11 out of registry. In fact, during 15 the blowing of bubbles it will be most convenient for these openings 10 and 11 to remain in registry, the user keeping his finger over the orifice 9, except when it is desired to permit a small quantity of the solution to flow out of that reservoir, and then 20 closing the orifice 9 quickly when a sufficient amount has passed out. Orifices 10 and 11 will in general be moved out of registry one with the other only when the user is through with the use of the device for the 25 time being. It will be seen that the rotatable tube 1 in connection with the tube 7, the two having registering orifices 10 and 11, together constitute a valve controlling the flow of solution from the reservoir. The 30 orifice 9 will, in general, be so small that little or no flow of solution will occur through it; it will be, practically, a capillary orifice.

It will be apparent that, a small quantity 35 of solution having been passed to the pocket 4, if the user blow through the tube 1 a bubble will emerge from this pocket, will seat upon the cup 5, and will gradually enlarge as the user continues to blow. Desirably, 40 the bore of the mouth piece tube will be so small or the bore of the bent tube 3 will be so small, that considerable pressure will be required for material flow of air through the tube. In this way premature destruction 45 of the bubble by too great air pressure will be avoided, also the user by reason of the pressure required, will develop increased strength of lung. The pocket 4 is preferably of capacity to hold solution to make several 50 bubbles.

The reservoir 6 may be filled most readily by means of a pipette of the rubber bulb type; *i. e.*, a device of the general nature of the ordinary fountain pen filler. Of course, 55 before filling the reservoir the cap 8 will be removed, after which the reservoir may be filled readily with the pipette, and the cap 8 replaced.

What I claim is:—

30 1. The combination with a reservoir having a tube passing through it and forming a part of it, of a blowing tube located within said reservoir tube and fitting tightly therein, and provided at one end with a cup 55 forming a bubble seat, the said tubes pro-

vided with apertures adapted to register and thereby to place the blowing tube in communication with the reservoir.

2. The combination with a reservoir having a tube passing through it and forming a part of it, of a blowing tube located within said reservoir tube and fitting tightly therein, and provided at one end with a cup forming a bubble seat, the said tubes provided with apertures adapted to register and thereby to place the blowing tube in communication with the reservoir, said blowing tube rotatable within the reservoir tube to bring such apertures into or out of registry. 70

3. The combination with a reservoir having a tube passing through it and forming a part of it, of a blowing tube located within said reservoir tube and fitting tightly therein, and provided at one end with a cup forming a bubble seat, the said tubes provided with apertures adapted to register and thereby to place the blowing tube in communication with the reservoir, said blowing tube rotatable within the reservoir tube to bring such aperture into or out of registry, and 80 means for limiting rotation of the one tube with respect to the other. 85

4. The combination with a reservoir having a tube passing through it and forming a part of it, of a blowing tube located within said reservoir tube and fitting tightly therein, and provided at one end with a cup forming a bubble seat, the said tubes provided with apertures adapted to register and thereby to place the blowing tube in communication with the reservoir, there being a 95 solution pocket at the base of the said cup. 100

5. The combination with a blowing tube formed in sections connected together, one of such sections having an enlargement forming a bubble seat, of a reservoir fitting over one of such sections, and having a tubular projecting portion, such projecting portion and the tube section upon which it is mounted having the one a projecting pin and the other a slot in which such pin works, there being a gap in such slot permitting disconnection of the pin from the slot, and permitting removal of the reservoir upon disconnection of the two sections of such tube. 105

6. The combination with a blowing tube formed in sections connected together, one of such sections having an enlargement forming a bubble seat, of a reservoir fitting over one of such sections, and having a tubular projecting portion, such projecting portion and the tube section upon which it is mounted having the one a projecting pin and the other a slot in which such pin works, there being a gap in such slot permitting disconnection of the pin from the slot, and permitting removal of the reservoir upon disconnection of the two sections of such tube, said reservoir and tube adapted for rotation, limited by engagement of the pin 110 120 125 130

with one end or the other of the slot, and having apertures adapted to place the reservoir and the bore of the tube in communication with the pin in one position in the slot, the said apertures being out of registry with the pin in another position in the slot.

5 In testimony whereof I have signed this

specification in the presence of two subscribing witnesses.

RAFAEL DIAZ BUITRAGO.
